UNITED STATES PATENT OFFICE.

BENJAMIN F. MACKALL, OF NORFOLK, VIRGINIA.

DESIGN FOR A BADGE-PIN.

No. 38,299.

Specification for Design.

Patented Oct. 30, 1906.

Application filed May 11, 1906. Serial No. 316,390. Term of patent 3½ years.

To all whom it may concern:

Be it known that I, BENJAMIN F. MACKALL, a citizen of the United States, residing at Norfolk, in the county of Norfolk and State of Virginia, have invented a new, original, and ornamental Design or Badge-Pins, of which the following is a description, reference being had to the accompanying drawing, forming part thereof.

The figure shown is a face view of a pin, showing my new design.

I claim—

The ornamental design for a badge-pin, as shown.

B. F. MACKALL.
